Des. 230,570
Patented Mar. 5, 1974

230,570

COLLAPSIBLE TUBE

Eugene L. Hall, 11 Martin Place, Chatham, N.J. 07928

Filed Feb. 7, 1972, Ser. No. 224,412

Term of patent 14 years

Int. Cl. D9—03

U.S. Cl. D9—194

FIG. 1

FIG. 2

FIG. 3

FIG. 4

FIG. 5

FIG. 1 is a perspective view of a collapsible tube embodying my new design;

FIG. 2 is a front elevational view of FIG. 1;

FIG. 3 is a side elevational view of FIG. 1;

FIG. 4 is a top plan view of FIG. 1;

FIG. 5 is a bottom plan view of FIG. 1.

I claim:

The ornamental design for a collapsible tube, as shown.
